UNITED STATES PATENT OFFICE

162,758

PUPPET

Robert E. Smith, New Rochelle, N. Y., and Milton Neil, Mountainview, N. J.; said Neil assignor to said Smith

Application September 29, 1949, Serial No. 5,224

Term of patent 14 years

(Cl. D34—4)

To all whom it may concern:

Be it known that we, Robert E. Smith and Milton Neil, a citizen of the United States, residing at New Rochelle, New York, and a citizen of the United States, residing at Mountainview, New Jersey, respectively, have invented a new, original, and ornamental Design for a Puppet, of which the following is a specification, reference being had to the accompanying drawing, forming part thereof.

Fig. 1 is a side view of the puppet, showing our new design.

We claim:

The ornamental design for a puppet, as shown.

ROBERT E. SMITH.
MILTON NEIL.
